CLAIM

The ornamental design for a pair of bin handles, as shown and described.

DESCRIPTION

FIG. 1 is a front, bottom perspective view of a first embodiment of a pair of bin handles, showing my new design;
FIG. 2 is a front elevation view thereof;
FIG. 3 is a rear elevation view thereof;
FIG. 4 is a left side elevation view thereof;
FIG. 5 is a right side elevation view thereof;
FIG. 6 is a top plan view thereof;
FIG. 7 is a bottom plan view thereof;
FIG. 8 is an exploded view thereof;
FIG. 9 is a front and bottom perspective view of a second embodiment of the pair of bin handles;
FIG. 10 is a front view thereof;
FIG. 11 is a rear view thereof;
FIG. 12 is a left side view thereof;
FIG. 13 is a right side view thereof;
FIG. 14 is a top view thereof;
FIG. 15 is a bottom view thereof; and,
FIG. 16 is an exploded view thereof.

The broken lines in the figures illustrate portions of the pair of bin handles that form no part of the claimed design.

1 Claim, 16 Drawing Sheets
